(57) CLAIM

I claim the ornamental design for a sole for sports footwear, as shown and described.

DESCRIPTION

FIG. 1 is a perspective view of a sole for sports footwear,
showing my new design;

FIG. 2 is a bottom view thereof;

FIG. 3 is a right side view thereof;

FIG. 4 is a front view thereof;

FIG. 5 is a rear view thereof; and,

FIG. 6 is a left side view thereof.

Any surfaces, or portions of surfaces, that are not shown form no part of the claimed design.
